UNITED STATES PATENT OFFICE.

CECIL DAVIS, OF GLASGOW, SCOTLAND, ASSIGNOR TO RADIO CORPORATION OF AMERICA, A CORPORATION OF DELAWARE.

WIRELESS DIRECTION-FINDING APPARATUS.

Application filed June 12, 1923, Serial No. 644,857, and in Great Britain June 16, 1922.

It has been found when using a closed loop aerial on board ship for direction finding purposes that errors are apt to creep in owing to the lack of symmetry in the two halves of the loop, and that this lack of symmetry is caused by the presence of adjoining metal structures or machines; for instance, a steel frame wireless telegraph house or cabin, the hatch of an engine room which is sometimes open and sometimes closed, a tank on deck and the like, have led to errors because these parts render the loop asymmetrical.

The object of this invention is to overcome this difficulty and to prevent the errors due to this cause.

According to the invention I provide between the loop and the cause of the lack of symmetry a screen which is connected to the ship's structure. Preferably this screen consists of a number of parallel wires stretched in a horizontal plane about midway between the loop and the nearest point of the cause of trouble. The wires should be preferably arranged symmetrically with respect to the loop and all the corresponding ends of the wires should be connected together and to the ship's structure at each end of the screen.

If a screen is provided at one end of the loop, then a similar screen should be provided in a similar position with respect to the other end.

The invention is illustrated by the accompanying diagrammatic drawing which shows the actual arrangement of a loop on board a ship, in which errors as described above were found to occur and the arrangement of the screen by which these errors were obviated.

Fig. 1 is a diagram showing of a loop above two disturbing means on board a ship with a screening means arranged therebetween and

Fig. 2 shows a single disturbing means beneath a loop and a screen arranged above the disturbing means with a balancing screen.

Referring to Fig. 1 *a* is the loop supported on a structure *b* above a steel frame wireless telephone house *c* and a hatch *d* which is sometimes opened and sometimes shut. The presence of the house *c* and the hatch *d* caused errors in the working of the direction finding apparatus. *e* is a screen which has been erected and by which the errors are obviated. It consists of a number of par-

allel wires stretched approximately horizontally and about twelve inches apart, and so arranged as to screen the whole of the loop from both the house *c* and the hatch *d*. The wires are connected together at each end and the whole screen is connected to the main metal structure of the ship.

Fig. 2 shows an arrangement very similar to Fig. 1 in which a screen *e* is positioned between the loop *a* and a hatchway *d* so as to shield the loop from any disturbing effects. A second screen *e* is symmetrically positioned opposite the screen *e* above the hatchway *d* for the purpose of balancing.

Having described my invention, what I claim is:

1. The method of conducting signals which consists of utilizing the electromagnetic component of ether waves which have become distorted by nearby conducting mediums, compensating for the effect of these distortions by screening the conducting means from said distortional effects and compensating the effects of such screening on the conducting means by a second screening effect symmetrical with reference to said first screening effect and conducting means.

2. The method of balancing the effect of directional waves on apparatus designed for locating them, consisting of shielding against irregularities caused by conducting projections or depressions beneath the locating apparatus and balancing the effect of said shield on the locating apparatus by a second shield of symmetrical proportions located in the same relative position on the opposite side of said locating apparatus.

3. The method of making corrections on directional antenna on ships and the like metallic structures which consists of balancing the irregularities in field distribution caused by such metallic structure by causing a plurality of irregularities of equal and opposite force to balance each other and the irregularities in field distribution caused by such metallic structures.

4. In combination, a direction finding loop antenna, field distorting devices consisting of irregular shaped structures, shielding means located between said loop and distorting devices, and means equal and opposite in effect to the first shielding means for neutralizing the effect of said first mentioned shielding means on said loop.

5. In wireless direction finders for ships

and the like having interfering metallic structures, a radiant energy absorbing member whose pointing position is subject to inherent error due to the distorted field caused by reradiation from the metallic structures, and shielding means comprising a plurality of parallel wires interposed between said energy absorbing member and the metallic structure and connected to the metallic structure.

6. In wireless direction finders for ships and the like having interfering conducting

structures, a radiant energy absorbing member whose pointing position is subject to inherent error due to distorted field caused by interfering conducting structures, screening means between the interfering conducting structure and the radiant energy absorbing means, and a balancing screen associated with said energy absorbing means to counteract the effect of the screening means on said radiant energy absorbing means. ¹⁵
